(57) **CLAIM**

The ornamental design for a dispenser cartridge and pitcher, as shown.

DESCRIPTION

FIG. 1 is a perspective view of a dispenser cartridge and pitcher illustrating our new design;

FIG. 2 is a left side elevational view of the design of FIG. 1; FIG. 3 is a right side elevational view of the design of FIG. 1; FIG. 4 is a front side elevational view of the design of FIG. 1; FIG. 5 is a back side elevational view of the design of FIG. 1; FIG. 6 is a top planar view of the design of FIG. 1;

FIG. 7 is a bottom planar view of the design of FIG. 1;

FIG. 8 is a perspective view of the design in an alternate position;

FIG. 9 is a left side elevational view of the design of FIG. 8; FIG. 10 is a right side elevational view of the design of FIG. 8;

FIG. 11 is a front side elevational view of the design of FIG. 8;

FIG. 12 is a back side elevational view of the design of FIG. 8;

FIG. 13 is a top planar view of the design of FIG. 8; and,

FIG. 14 is a bottom planar view of the design of FIG. 8.
